(57) **CLAIM**

The ornamental design for a multiple guitar stand, as shown and described.

DESCRIPTION

FIG. 1 is a perspective view of a multiple guitar stand in the extended position;

FIG. 2 is a left-side view of a multiple guitar stand in the extended position;

FIG. 3 is a right-side view of a multiple guitar stand in the extended position;

FIG. 4 is a top view of a multiple guitar stand in the extended position;

FIG. 5 is a back view of a multiple guitar stand in the extended position;

FIG. 6 is a front view of a multiple guitar stand in the extended position;

FIG. 7 is a bottom view of a multiple guitar stand in the extended position;

FIG. 8 is a perspective view of a multiple guitar stand in the retracted position;

FIG. 9 is a left-view of a multiple guitar stand in the retracted position;

FIG. 10 is a right-view of a multiple guitar stand in the retracted position;

FIG. 11 is a top view of a multiple guitar stand in the retracted position;

FIG. 12 is a back view of a multiple guitar stand in the retracted position;

FIG. 13 is a front view of a multiple guitar stand in the retracted position; and,

FIG. 14 is a bottom view of a multiple guitar stand in the retracted position.

The elements shown in broken lines do not form any part of the claimed design. The break lines shown in FIGS. 1, 4, 5, 6, 7, 8, 11, 12, 13 and 14 are not part of the claimed design and represent that no particular length is claimed.

1 Claim, 14 Drawing Sheets
